UNITED STATES PATENT OFFICE

ADOLPH C. RECKER, OF OAKVILLE, CONNECTICUT, ASSIGNOR TO WATERBURY MFG. CO., OF WATERBURY, CONNECTICUT, A CORPORATION.

PORTABLE ELECTRIC LAMP.

1,166,003.

Specification of Letters Patent. Patented Dec. 28, 1945.

Application filed October 25, 1915. Serial No. 57,652.

To all whom it may concern:

Be it known that I, ADOLPH C. RECKER, a citizen of the United States, residing at Oakville, in the county of Litchfield and State of Connecticut, have invented a new and useful Improvement in Portable Electric Lamps; and I do hereby declare the following, when taken in connection with the accompanying drawings and the characters of reference marked thereon, to be a full, clear, and exact description of the same, and which said drawings constitute part of this application, and represent, in—

Figure 1 is a side view of a portable electric lamp constructed in accordance with my invention. Fig. 2 a top or plan view of the same. Fig 3 an underside view on an enlarged scale. Fig. 4 a broken transverse sectional view showing the parts in the open position. Fig. 5 a similar view showing the parts in the closed position.

This invention relates to an improvement in portable electric lamps, and particularly to portable electric lamps which are of the so called candle type, for the reason that the holder is in the form of a candlestick.

The object of this invention is to provide simple means for opening and closing the circuit through the lamp, and the invention consists in the construction hereinafter described and particularly recited in the claims.

In carrying out my invention I employ a base 2 struck up from sheet metal and provided with a handle 3 formed with a slot 4 for the purpose as will hereinafter appear. Mounted on the base is a cup 5 within which is a socket 6 which receives the lower end of a battery container 7, this container preferably being in imitation of a candle and carries an incandescent bulb 8 at its upper end. This container receives the usual battery 9 the lower end of which is exposed through openings 10 formed in the base, cup, and socket. Pivotaly mounted in the base is a contact lever 11 the inner end 12 of which is in line with the exposed end of the battery 9, and the other end is pivotally connected with the finger-piece 14 which is provided with a pin 15 adapted to engage with the upper end of the slot 4 through which the finger-piece extends. Also mounted in the base is a spring 16 which

bears upon the contact lever 11 near its inner end, the tendency of the spring being to move the end 12 out of contact with the battery, and to lift the finger-piece away from the handle 3, which is the open position of the lamp, as shown in Fig. 4. To close the circuit through the lamp or to light the lamp, the finger-piece 14 will be moved downward slightly or pressed against the handle 3 which forces it downward so that the pin 15 enters the slot 4 and engages with the upper end thereof as shown in Fig. 5 of the drawings. This downward movement of the finger-piece lifts the inner end 12 of the contact lever 11 and forces it into engagement with the lower end of the battery as also shown in Fig. 5 of the drawings, so as to close the circuit through the lamp. It will be understood that one pole of the lamp is connected with the battery and the other through the container 7 with the base, and so that when the contact lever touches the battery the circuit is closed.

To open the circuit it is only necessary to move the finger-piece away from the handle which can readily be done by a slight movement of the thumb or one finger so as to move the pin 15 out of the slot 4 and allow the spring 12 to act to move the inner end of the contact lever out of engagement with the battery and at the same time lift the finger-piece away from the handle. This device provides simple means by which a portable electric light of the candlestick type may be readily operated by the thumb or one finger.

I claim:—

1. A portable electric lamp comprising a base, socket and container, said base provided with an upwardly projecting handle said handle formed with a slot, a contact lever pivoted in the base, a finger-piece pivotally connected with the outer end of said lever and projecting upward through said slot in the handle and provided with a pin adapted to engage with the upper end of said slot.

2. A portable electric lamp comprising a base provided with a handle formed with a slot, a socket mounted on said base, a container adapted to be mounted in said socket said container provided at its upper end with an incandescent bulb, an opening through

the top of the base and said socket, a battery cell in said container the bottom of the battery being exposed through the opening in the top of the base, an operating lever pivotally mounted in the base and having its inner end in line with said opening, a spring bearing on said contact-lever, a finger-piece

pivots connected with the upper end of said lever and projecting upward through said base, a slot in said handle, said finger-piece provided with a pin adapted to engage with the upper end of said slot. 10

ADOLPH C. RECKER.
